TOY

Kenneth W. Taplin, Minneapolis, Minn.

Application November 13, 1944, Serial No. 563,128

8 Claims. (Cl. 46—191)

My invention relates to improvements in toys and has for an object thereof to provide a simple, durable, inexpensive and easily operated sound producing toy having a plurality of moving parts presenting an entertaining display.

More specifically, it is an object of the invention to provide a rotary member, revoluble in a mounting or rollable along a support, such member carrying a plurality of abutments and pivoted strikers swingable, by gravity, to strike said abutments as said member turns, a feature of the invention resides in the employment of rails about the axis of the revoluble member having the dual function of providing pivotal supports for some of the strikers and abutments for others thereof.

Another feature of the invention resides in the provision of an axial abutment against which the strikers strike, a further feature residing in the arrangement of the strikers in pairs successively along the revoluble member with the strikers of each pair overreaching opposite sides of the axial abutment. A still further feature of the invention resides in disposing the strikers which are pivoted to the same rail so that they overreach the axial abutment at opposite sides thereof progressively along the revoluble member.

Other objects of the invention reside in the novel combination and arrangement of parts and in the details of construction hereinafter illustrated and/or described.

In the drawings, Fig. 1 is a side elevational view of a toy embodying my invention; Fig. 2 is a sectional view taken on the line 2—2 of Fig. 1; Fig. 3 is an elevational view of an alternate form of the invention, and Fig. 4 is a sectional view taken on the line 4—4 of Fig. 3.

Referring to the drawings wherein similar parts are designated by similar reference characters, it will be seen that the form of my invention shown in Figs. 1 and 2 comprises a mounting A and a revoluble member B supported thereby.

The mounting A consists of a base 10 to which posts 11, 12 are secured.

The revoluble member B includes a shaft 13, spaced heads X thereon, and rails 14 carried at their ends by said heads. One end of the shaft 13 is journaled in the post 11 while the other end of said shaft is journaled in the post 12, said latter end of the shaft extending through said post 12 and being provided with a crank 15, which when turned, rotates the shaft 13 and with it the heads X and rails 14. The heads X are spider-like, each head being formed with a hub portion 16 fixed to the shaft 13 and each head having four radial arms 17 spaced apart

ninety degrees, the arms 17 of the two heads A registering with each other. The rails 14 are rods, the opposite ends of each thereof being secured in the ends of two registering arms 17 of the heads X.

Pivoted at their ends on the rails 14, are strikers a, a¹, b, b¹, c, c¹, d and d¹ which may be of any suitable form, preferably of the bar-like or paddle-like form shown. Conveniently, this form of striker is pivoted to a rail 14 by forming a hole edgewise through the striker and threading it on the rail before the rail is secured to its respective arms 17 of the heads X. Said strikers are arranged in pairs at opposite sides of the shaft 13 in successive zones lengthwise of the revoluble member B, there being one pair of strikers to each zone, the strikers of each pair being pivoted to diametrically opposed rails 14. Strikers a, a¹ are the strikers of one pair in one zone transversely of the member B, strikers b, b¹ the strikers of a second pair in the next zone, strikers c, c¹ the strikers of a third pair in a third zone and strikers d, d¹ the strikers of a fourth zone.

Each of the strikers a, a¹, b, b¹, c, c¹ and d, d¹ is of a length and is disposed to extend between the shaft 13 and a rail 14 other than that on which such striker is pivoted. Thus, the shaft 13 constitutes an abutment or anvil against which each striker impinges upon swinging in one direction, an abutment or anvil against which such striker impinges upon swinging in the opposite direction being constituted by a rail 14 other than the one pivotally supporting such striker. So arranged, the opposed strikers of each pair swing, by gravity, each striking the shaft 13 and then its respective abutment rail 14, or vice versa, upon each revolution of the member B, resulting in active movements of the strikers accompanied with noise-making impacts thereof against their abutments. Coloring of the strikers a, a¹, b, b¹, c, c¹ and d, d¹ in contrasting colors adds to the display of movement and their formation to provide for different tones upon impact enhances the noise effect. In said latter respect, the invention contemplates the formation of the strikers from different materials in different cross-sectional designs, as well as the formation of holes 18 in bar-like strikers, as shown in Fig. 1 of the drawings.

Strikers may be employed in as many pairs as desired and those of them that are pivoted along the same rail 14 will be disposed alternately at opposite sides of the shaft 13 after the fashion of the strikers a, c¹ and b, d¹ and c, a¹ and d, b¹.

Reference being had to the alternate form of

my invention shown in Figs. 3 and 4, it will be seen that the rails 19 are secured to circular heads 20 which may roll along the floor or other supporting surface and that the revoluble member E, composed of said rails 19 and heads 20, may be pushed or pulled, as by a tongue 21 connected to trunnions 22 on said heads 20. This form of toy is devoid of an axial shaft or abutment and has three rails 19. Each of these rails 19 has a striker e pivoted thereto and each striker is of such a length and so disposed that it swings on its supporting rail 19, first against one of the other rails 19, and then against the third rail, upon each revolution of the member E. Each rail 19, of course, may pivotally support any number of strikers that may be accommodated within the length of the revoluble member E. As compared with the first described form of my invention, each striker e of the second described form strikes two rails constituting abutments therefor instead of one such rail and an abutment shaft disposed inwardly of said rails.

Changes in the specific form of my invention, as herein described, may be made within the scope of what is claimed without departing from the spirit of my invention.

Having described my invention, what I claim as new and desire to protect by Letters Patent is:

1. In a toy, a member revoluble about a horizontal axis and consisting of an axial shaft, heads on said shaft, and rails mounted at their ends on said heads and spaced apart circumferentially about the shaft, there being two pairs of rails, the rails of each pair being oppositely disposed relative to the shaft, strikers carried by each rail, said strikers being arranged in pairs in successive zones transversely of the revoluble member, one pair to each zone, the strikers of each pair being disposed at opposite sides of said shaft, one striker of each pair being pivotally supported at one end by one rail of one pair and the other striker of such pair of strikers being pivotally supported at one end by the other rail of such pair, each striker extending from its supporting rail between said shaft and one of the rails of the other pair and adapted, by gravity, to swing back and forth against such rail and said shaft to strike each thereof upon each revolution of said member.

2. In a toy, a member revoluble about a horizontal axis and consisting of an axle, heads on said axle and rails spaced circumferentially about the axle and mounted at their ends on said heads, a plurality of strikers, one for each of different rails, each striker being pivoted at one end thereof to its respective rail and extending therefrom to a position between said axle and another of said rails, and adapted, by gravity, to swing back and forth against such rail and said axle to strike each thereof upon each revolution of said member.

3. In a toy, a member revoluble about a horizontal axis and consisting of an axle, heads on said axle and rails spaced circumferentially about said axle and mounted at their ends on said heads,

a succession of strikers, there being a number thereof for each rail, each striker being pivoted at one end thereof to its respective rail and extending therefrom between said axle and another of said rails and adapted, by gravity, to swing back and forth against such rail and said axle to strike each thereof upon each revolution of said member, those of said strikers pivoted to the same rail being disposed, progressively thereof, at opposite sides of said axle.

4. In a toy, a member revoluble about a horizontal axis and consisting of a pair of heads and a shaft and rails extending from one head to the other, said rails being spaced circumferentially about said shaft, a succession of strikers, there being a number thereof for each rail, each striker being pivoted at one end thereof to its respective rail and extending between said shaft and another of said rails and adapted, by gravity, to swing back and forth against such rail and said shaft to strike each thereof upon each revolution of said member.

5. In a toy, a member revoluble about a horizontal axis, said member including an inner abutment and outer abutments extending axially of said member, the outer abutments being spaced circumferentially about said inner abutment, and a plurality of strikers, each striker being pivotally supported at one end thereof by one of said abutments and extending between two of the other of said abutments and adapted, by gravity, to swing back and forth against said two abutments to strike each thereof upon each revolution of said member.

6. In a toy, a member revoluble about a horizontal axis, said member including a plurality of rails spaced circumferentially about said axis, strikers, one for each rail, each striker being pivoted at one end thereof to its respective rail and extending therefrom inside of another of said rails and adapted, by gravity, to swing away from and back against such rail to strike the same upon each revolution of said member.

7. In a toy, a member revoluble about a horizontal axis, said member including a plurality of rails spaced circumferentially about said axis, strikers, one for each of different rails, each striker being pivoted at one end thereof to its respective rail and being of a length to reach to another of said rails and adapted, by gravity, to swing away from and back against such rail to strike the same upon each revolution of said member.

8. In a toy, a member revoluble about a horizontal axis, said member including a plurality of rails spaced circumferentially about said axis, strikers, one for each rail, each striker being pivoted at one end thereof to its respective rail and extending between two of the other rails and adapted, by gravity, to swing back and forth against said two rails to strike each thereof upon each revolution of said member.

KENNETH W. TAPLIN.
